GUN

David M. Williams, Godwin, N. C.

Application March 19, 1935, Serial No. 11,879

34 Claims.

(Cl. 89—3)

The present invention relates to guns, and especially machine guns.

The present day military machine guns, as usually designed, have such weight and their parts are so constructed as to require high intensity ammunition to operate the same.

By "high intensity ammunition" is meant ammunition which on firing develops high pressure, and imparts to the bullet or projectile high velocity and great striking energy. It is a characteristic of high intensity ammunition that it develops a high kinetic energy.

In accordance with the present invention, machine guns which would normally require high intensity ammunition to operate the same are operated by low intensity ammunition.

By "low intensity ammunition" is meant ammunition which possesses low ballistic properties. High intensity military ammunition, generally speaking, designates or identifies ammunition of which the bullet is of large calibre but as the term "high intensity" is used in the present specification, it does not necessarily mean that the bullet is of large calibre. The bullet may be of small diameter or calibre and the cartridge be of such a character as to develop the high pressure and the high velocity which characterizes the high intensity ammunition. In other words, even though the calibre of the bullet may be small, the high intensity ammunition has high ballistic properties. It follows, therefrom that the term "low intensity ammunition" as used in the present specification does not necessarily refer to a cartridge having a bullet of any specific calibre. The calibre of the bullet may be large, relatively speaking, but the cartridge has low ballistic properties.

In order to illustrate more specifically what is meant in the present specification by the terms "high intensity ammunition" and "low intensity ammunition" and to show that these terms are not limited to more specific diameter of the bullet, the following examples are given:

A gun having operating parts, including breech mechanism, of such weight and construction which normally would have to be operated with calibre .30 1906 Gov't. ammunition, may be operated, in accordance with the present invention, by using a low calibre .22 rim fire cartridge.

In this case the bullet of the cartridge which is used to operate, in accordance with the present invention, has a smaller diameter than the calibre .30 1906 Gov't. cartridge.

A further example is as follows:

A machine gun having mechanism of such

weight and construction that requires calibre .30 1906 Gov't. cartridges for operation, may be operated, in accordance with the present invention, with low intensity cartridges having bullets of larger diameters, such as the .45 automatic pistol cartridges that are used in the Government model pistol calibre .45.

The above examples bring out the fact that the calibre of the bullet is not the determining factor involved in the present invention, but that the determining factor is that machine guns requiring an ammunition developing a high recoil can be operated with ammunition developing a low recoil. It is, of course, quite evident that the recoil in effect depends upon whether the cartridge is a high intensity cartridge or low intensity cartridge.

In accordance with the present invention, when using low intensity ammunition, a portion of the low pressure gases produced by firing of the cartridges reacts upon the pressure area of a movable member, hereinafter termed the "actuator", to thereby increase the kinetic effect of the gases. In other words, the operation of the gun, irrespective of whether it is a recoil operated gun or gas operated gun, is effected by having low pressure gases generated by low intensity ammunition acting upon a certain predetermined pressure area of the movable member, and this area may be made smaller or larger in order to decrease or increase the operating force. In other words, broadly, in accordance with the present invention, the energy present in the low pressure gases may be distributed over a smaller or larger area to generate a force which is sufficient to operate parts of the gun which heretofore have only been operated by high pressure gases. One of the basic features of the present invention is that the operating energy can be controlled by using a constant gas pressure and varying the pressure area over which it acts or that the pressure area can be held constant, and the characteristics of the cartridge controlled so the gas pressure generated upon firing the cartridge may be varied.

The present invention in one of its forms comprises the combination with a gun having a bolt mechanism provided with parts of large calibre weight and resistance, but adapted to function with sub-calibre ammunition, with a sub-calibre barrel for said gun, and a movable actuating member for said bolt mechanism including a gas chamber receiving the powder gases of combustion upon firing of the gun, said chamber having a pressure area of such extent as to effect operation of the bolt mechanism upon firing of the sub-

calibre ammunition in said gun. In one form of the invention, the actuating member for the bolt is mounted in telescopic relationship to the barrel and is arranged to form a gas chamber at the rear 5 end of the barrel as it moves rearwardly thereof.

The invention is also broadly directed to a firearm having the usual bolt mechanism, ammunition chambering means, and an actuator in which means are provided, in addition to the usual cartridge chamber, for venting a part of the expanding gases, when the bolt member after firing of the firearm, has moved a predetermined distance rearwardly.

The actuating member has a sleeve extending 15 forwardly from the rear portion thereof and fitting slidably on the rear end of the barrel. This sleeve has gas venting means closed when the sleeve is in ammunition firing position and open upon the sleeve moving a predetermined distance 20 rearwardly. A gas tight packing, which may be in the form of the ordinary piston ring, such as used on automobile pistons, is provided between the rear end of the machine gun barrel and the actuator sleeve.

It is also an object of the present invention to provide in a firearm having a bolt mechanism, means for actuating the bolt and ammunition chambering means cooperating with said members, a cartridge having the forward end of its 30 powder case projecting therefrom, and means associated with the barrel of the firearm and the powder case chambering means to cause equalization of gas pressure within and without said projecting end of the powder case.

In the preferred form of the invention, the powder case projects forwardly of the cartridge chamber member and into the rear end of the barrel, the latter being recessed to receive the projecting end of the powder case, the recess 40 having a chamfered peripheral wall to permit equalization of the gas pressure inside and outside of said projecting end.

The present invention also contemplates certain novel details of combination, construction 45 and arrangement of parts of the improved machine gun, whereby certain important advantages are obtained as will be more fully described hereinafter, and pointed out in the claims, it being understood that the invention is susceptible to 50 various changes in construction which may be made within the scope of the claims, without departing from the spirit of the invention.

The present invention will be disclosed and fully explained by reference to the accompanying 55 drawings, wherein:

Figure 1 is a longitudinal vertical section of a machine gun in its closed or ready-to-fire position;

Figure 2 is a detail showing the muzzle end of 60 the stationary barrel of the gun;

Figure 3 is a longitudinal vertical section of the machine gun in its fully opened position;

Figure 4 is an enlarged longitudinal vertical section of a portion of the machine gun mechanism 65 showing the powder case and the relative position of the movable chamber means to the barrel when the gun is in its closed position substantially immediately after firing;

Figure 5 is a similar view showing the positions of said parts after the cartridge has been fired and has moved the gun mechanism to a partially retracted position;

Figure 6 is a similar view of the gun after firing showing the movable chamber means in its fully retracted position;

Figure 7 is an enlarged plan view showing the movable chamber means assembled with the extension member;

Figure 8 is a longitudinal section of the movable chamber showing the exhaust grooves 5 thereof;

Figure 9 is an end view thereof; and

Figure 10 is a transverse section along the line 10—10 of Fig. 3, showing the depressor plunger engaging different cam surfaces of the depressor 10 cam.

The machine gun has the usual receiver or gun casing means 10 comprising side plates 11, bottom plate 12, top plate 13, back plate 14, trunnion block 15, jacket 16, and cover 17 pivoted on 15 pin 18.

The receiver is provided with the usual trigger 19, pivoted at 20, said trigger cooperating with sear 21, the sear 21 operating under the influence of spring 22. As shown in Fig. 1, when the gun 20 is in its ready to fire position, the sear 21 engages the notched portion of the striker 23, the latter being provided with striker points 24 and 25. The striker member 23 is brought into the ready to fire position by means of the cocking lever 26. 25

Located within the bolt 27 are many of the parts above referred to, said bolt 27 being provided with a rearward portion 28 and a forward portion 29, which engages the rearward portion of the movable chamber 30 which is secured in any 30 suitable manner, for example, by threads 31 to the extension member 32, said extension member being provided with grooves 33, one on each side of the extension member to receive the bolt 27. 35

Secured to the left hand side plate of the receiver is a depressor feed cam 34 (shown in detail in Fig. 10), provided with two cam surfaces 35 and 36 adapted to cam the depressor 37, pivoted at 38, downwardly on the forward stroke of the bolt 27, said depressor 37 being provided with a 40 lug member 39 recessed to receive the depressor plunger 40 which is held against the left side plate 11, by means of a spring (not shown).

The lug member 39 at its upper portion is provided with an upper cam surface 41 adapted on 45 opening of the gun to engage the lower cam surface of cover cam 42, as shown in Fig. 3; the cover cam serving to partially depress the depressor 37 on the opening movement of the gun. The depressor is further depressed on the closing 50 of the gun by means of the depressor plunger 40 cooperating with the cam surface 36. The depressor lug 39 is provided at its lower portion with a lower cam surface 43 adapted to depress the cartridge 44, as more fully described herein- 55 after, the dotted lines in Fig. 3 showing the cartridge 44 in its depressed position.

The depressor lug 39 is provided with a further cam surface 41a positioned adjacent to the cam surface 41, the cam surface 41a being below 60 the cam surface 41, as shown in Fig. 4.

The cover spring 45 engages the depressor cam surface 41a, as shown in Figs. 1 and 4, respectively, said spring causing the lower cam surface 43 to engage the cartridge 44 and push downwardly 65 thereon, causing the shell head 47 to engage the extracting edge 48 of the extractor 46, which serves to extract the cartridge from the ammunition belt.

Attached to the side receiver plate is the cam 70 49 having a camming surface 50.

The actuator or movable member is identified as an entity by the numeral 30. This actuator comprises a rear portion 55 provided centrally thereof with a powder case chamber 51, as shown 75

In Fig. 5, adapted to receive the powder case 58. Extending from the rear portion 55 of the actuator is a recessed member 52 having a wall 53 and a gas chamber 54 connecting with the powder case chamber 51, but of much larger diameter. The wall 53 forms a sleeve surrounding the rear end of the barrel 59, said sleeve functioning as a bearing, support, or guide for the actuator and its associated parts. At the rear end of the gas chamber 54, there is provided adjacent the powder case chamber 51 a gas contact or pressure area 56.

A portion of the gas chamber 54 is provided for the escape of the residual gases present after the firing of the cartridge. The exhaust of the residual gases also functions to keep the gas chamber free from any elements of combustion. If these elements are present, there is a tendency for the actuator 30 to bind or freeze to the rear end of the barrel 59 and thereby cause malfunction of the gun.

In the form of the invention shown in Figs. 8 and 9, the exhaust means comprise grooves 57 which are arranged concentrically of the axis 25 of the gas chamber 54, the latter, as shown, being in the form of a cylinder. It is within the province of the present invention to have the gas chamber 54 assume any geometric form, the only limitation being that it must have the same 30 shape as the barrel member. When the gas chamber 54 is a cylinder, the grooves 57 may be arranged concentrically of the axis of the cylinder.

The grooves 57 are merely illustrative of one 35 suitable form of the means which may be used to allow the escape of the residual gases from the gas chamber 54. Although the grooves have been found most satisfactory, instead of using grooves, the wall 53 of the actuator 30 may be 40 provided with holes or any other recess which allows the residual gases to escape at the desired time interval during the operation of the gun.

The exhaust means or gas venting means is 45 closed when the actuator sleeve is in the ammunition firing position, and open when the sleeve has moved a predetermined distance upon the rearward stroke of the actuator.

The barrel 59 having a bore 60 is provided at 50 its rear end with a chamfer 61 leading into the bullet seat 62. The rear end of the barrel has an annular face 63 adapted in one of its positions to come in close contact with the gas contact face 56. As shown in Fig. 1, the barrel 59 at its rearward end is fixedly mounted in the 55 sleeve 64. The muzzle end of the barrel is also stationarily mounted in the forward end of the jacket 16, as shown in Fig. 2.

It is to be noted that the powder case 58 has 60 its front end 58a protruding beyond the forward end of the powder case chamber 51 and preferably, although not necessarily, into the rear end of the barrel bore.

As shown in Fig. 4, the crimped end 58a of the powder case 58 extends into the chamfered portion of the barrel bore. The chamfered portion allows the bullet 58b to enter the bullet seat 62 without shaving off any material, for example, lead or the like, from the bullet.

The protrusion of the powder case, as shown, 70 causes the entire bullet to be placed into the barrel bore before firing, and thereby prevents the shearing off or accumulation of any lead or other parts of the bullet on the rear end of the barrel when the cartridge is fired.

As shown in Fig. 4, the bullet has travelled a short distance in the barrel bore.

The chamfered bore further serves to allow the gases to pass around the front end 58a of the powder case to impinge against the gas contact area 56 and the annular face 63 of the rear end of the barrel. The gases being free to pass around the outside wall of the front of the powder case produces the same pressure on the outside wall as on the inside wall, thereby neutralizing the action of the gases which would swell out the front end of the powder case.

The above construction provides means for preventing the front end of the powder case, which protrudes beyond the gas contact wall, from 15 swelling. Obviously, the construction is merely illustrative of one form which has been found satisfactory, and other constructions may be employed to obtain the same result. Broadly, it 20 may be stated that the above arrangement provides means for causing equalization of the gas pressure within and without the projecting end of the powder case.

It is to be noted that the barrel 59 has mounted thereon at its rearward portion a barrel sleeve 25 64 provided at its forward end with an interior annular face 65, said sleeve being spaced from the outside of the barrel to provide an annular recess or chamber 66. The exhaust gases and elements of combustion pass out of the grooves at 30 the extreme forward ends thereof into the chamber 66, and the elements of combustion are deposited at the forward end thereof.

In accordance with the above, the cylindrical member surrounds the barrel and sleeve in spaced 35 relation thereto, the barrel being secured in its forward end, and the cylinder being open at its rear end. It is within the province of the present invention to change the shape of the cylinder, and in the claims, the term "cylinder" is to be 40 given this broad interpretation.

At or near the rear end of the barrel 59 a piston ring 67 is fitted, said piston ring serving as a gas seal.

The operation of the gun is as follows: 45

The gun is shown in its closed ready-to-fire position in Fig. 1. The pull on trigger 19 causes it to pivot on pin 20 and its forward end to pull sear 21 downwardly, disengaging the sear with striker 23. The striker then moves forwardly 50 under the influence of spring 23a, causing the striker point 24 to fire the cartridge, as shown in Fig. 4. Fig. 4 also shows that when the cartridge is fired, the gases escaping from the mouth of shell 58a will follow the rear end of chamfer 55 61 and come into contact with the rear face 63 of the barrel 59 and also with the gas contact face 56 of the actuator 30, as shown in Fig. 4. The pressure of the gases at this time is equal on the outside and inside of front end of powder case 60 58 at the crimped and adjacent portions 58a, preventing the bulging or swelling of the front end of the powder case. The gases acting on stationary face 63 of stationary barrel 59 and on gas contact face 56 in actuator 30 cause the actuator 30 to have a powerful or violent rearward movement. Different stages of this movement are shown in Figs. 5 and 6. As actuator 30 moves rearwardly, it carries extension 32, bolt 27 and their associated parts rearwardly. The depressor 37 acting under tension of spring 45 holds the head of cartridge 44, as shown in Fig. 4, in contact with extractor 46. The extractor 46 being mounted on extension 32 and depressor 37, pivoted at 38, on bolt 27 move as a unit rearward- 75

ly for a short distance. During this movement, the cartridge 44 is extracted from belt 44a, the latter being shown in Fig. 1.

As shown in Fig. 5, the actuator 30 and exhaust grooves 57 move to their respective positions relative to rear face 63 of barrel 59. During this said short movement, the actuator 30 and rear end of grooves 57 come to a position indicated at the point 57a, the forward end 58a of the powder case 58 remaining in the powder case chamber 51. At these positions, the residual gases have begun to escape through grooves 57 and into the barrel sleeve chamber 66. A continuation of this short movement is shown in Fig. 6. The rear ends 57a of exhaust grooves 57 occupy their most rearward position, and the powder case 58 is extracted from the powder case chamber 51. When these parts are in the respective positions above set forth, the exhaust of the residual gases and elements of combustion have been completed.

The actuator 30 having come to rest, the bolt 27 and its parts continue to move rearwardly under the influence of the momentum gained through the movement of actuator 30. The bolt mechanism continues rearwardly, carrying with it the fired powder case 58 and live cartridge 44. During this movement, the depressor 37 is cammed downward by cam 42, forcing live cartridge with it, as shown in Fig. 3. (Fig. 5 shows the intermediate position of the cartridge in the depressor.)

Immediately before the bolt comes to the full open position, the striker 23 is moved to the cocked position by cocking lever 26 operating against top plate 13.

The gun is now at the end of its recoiling movement, or stated differently, it is in its "opened" position.

40 In the closing or counter recoiling movement, the bolt moves forwardly under the influence of the usual recoil spring or bolt driving spring (not shown) carrying its associated parts, including the depressor 37. When depressor 37 has 45 moved a short distance forward, its plunger 40 contacts with cam surface 36 of cam 34, forcing the depressor to complete its downward movement carrying the cartridge 44 to the position indicated by dotted lines in Fig. 3, said cartridge 50 then being in line with the bore 60 of barrel 59.

In the final closing movement, the bolt contacts with actuator 30, driving it to the closed position. The depressor plunger 40 contacting with cam face 50 of cam 49 raises the depressor 55 37 to its uppermost position. The closed positions of the operating parts, including the depressor 37, bolt 27 and actuator 30, are clearly shown in Figs. 1 and 4, respectively.

The structure set forth, and especially the 60 structure of the actuator 30 and the manner in which it cooperates with the gun mechanism enables, as pointed out, the operation with low intensity ammunition, of a machine gun which normally would require high intensity ammunition 65 ballistically speaking. It has been discovered, in accordance with the present invention, that low intensity ammunition ballistically speaking be used to actuate a gun carrying operating parts which would normally require high intensity ammunition ballistically speaking, provided an actuator is used which is capable of multiplying the kinetic effect of the expanding gases produced by the firing of the cartridge.

It is desired to point out that the movable operating parts of large calibre machine guns

have a certain weight, and these parts are required in operation to move with a certain force through a certain distance to facilitate the loading and unloading of the long large calibre ammunition.

In accordance with the present invention, these parts are operated by using low intensity ammunition ballistically speaking, which may be under some circumstances sub-calibre ammunition and utilizing the pressure generated by the firing of the cartridge to generate the required recoiling effect, but having the gases act upon a certain contact area. This area is predetermined in accordance with all of the factors above set forth, namely, the weight of the operating parts of the gun, the stroke of the operating parts, the amount of resistance to be overcome, including spring resistance and frictional resistance, and the speed desired. The following are actual examples of guns constructed in accordance with the present invention:

1. A machine gun having operating parts weighing approximately 3 pounds, a bolt stroke of approximately 4 1/4 inches, and equipped with the regular calibre .30 springs, including the bolt driving spring, was caused to function satisfactorily by providing an actuator having a gas contact face 56 of .626 diameter, said gun being operated with regular low pressure calibre .22 rim fire cartridges.

2. A machine gun having operating parts weighing approximately 4 1/2 pounds, a bolt stroke of approximately 4 1/4 inches, and equipped with regular calibre .30 springs, including the bolt driving spring, was caused to function satisfactorily by providing an actuator having a gas contact face 56 of .875 diameter, said gun being operated with regular low pressure calibre .22 rim fire cartridges.

It is within the province of the present invention to have the ammunition receiving chamber long enough to chamber the entire cartridge or it may be longer than the cartridge. In that case, of course, no means are necessary to cause equalization of the gas pressure, since the powder case 45 does not project out of the cartridge chamber.

It is also within the province of the present invention to use the structure set forth with high intensity ammunition wherever the structure will adapt itself to the use of such ammunition.

The term "sub-calibre barrel" as used in the present application and in the claims, defines a barrel which is adapted to be used in conjunction with sub-calibre ammunition, as hereinbefore set forth.

As previously pointed out, a gun utilizing the present invention, can use .22 calibre rim fire cartridges. If the present invention was not embodied in the gun, and all the operating parts were of the same weight and construction, there 60 would be required calibre .30 1906 Gov't ammunition, or its equivalent, to function the gun. This brings out the point that in most cases, the diameter of the barrel bore will be sub-calibre to accommodate the smaller diameter bullet 65 but as pointed out in the previous discussion, the diameter of the barrel bore can, under some circumstances, be larger.

A further example is as follows:

A machine gun having mechanism of such 70 weight and construction that requires calibre .30 1906 Gov't cartridges for operation, may be operated, in accordance with the present invention, with low intensity cartridges having bullets of larger diameters, such as the .45 automatic pis-

tol cartridges that are used in the Government model pistol calibre .45.

This is an example of a gun in which the diameter of the barrel bore has been increased from the diameter which would be employed if the present invention had not been employed.

The present invention, while of particular value when incorporated in machine guns, may be incorporated in various kinds of firearms. It is desired to further point out that the basic principle herein disclosed whereby a gun may be operated with low intensity ammunition by employing a relatively large gas contact or pressure area, is disclosed in another form in my prior applications, Serial No. 514,252, filed February 7, 1931, and Serial No. 686,932, filed Aug. 26, 1933, and it is stated in said prior applications that the principle of utilizing a large gas contact or pressure area may be used for the operation of firearms in general. The present application is of similarly broad scope, and while particularly adapted for machine guns, is not limited thereto. The present application is a continuation-in-part of said prior applications.

25. It is desired to point out that the arrangement set forth in said prior application enables a gun having operating parts, including breech mechanism, of such weight and construction which normally would have to be operated with calibre .30 1906 Gov't. ammunition, to be operated by using low intensity ammunition, which may be a .22 rim fire cartridge, or it may be a cartridge such as a .45 automatic pistol cartridge that is used in the Government model pistol .45.

35. While the present invention has been described in connection with the gun illustrated in the drawings, it is recognized that it can be used in connection with all conventional types of machine guns including those usually known under the terms "gas operated machine guns" and "recoil operated machine guns". Such changes as are necessary are within the province of the ordinary worker skilled in the gun art.

The present application and the specific arrangements therein disclosed may incorporate the principles set forth in the prior application.

I claim:

1. In a machine gun having breech mechanism and ammunition feeding means of such weight and resistance as to normally require high intensity ammunition to operate the same; the combination of a stationary barrel, bolt means including a bolt, a reciprocating actuator provided with means for chambering a low intensity cartridge and a gas chamber member, said actuator having a gas chamber formed therein communicating with said cartridge chambering means, said gas chamber member being mounted in telescopic relationship with the rear portion of the barrel, the gas chamber member and the barrel being arranged to prevent the escape of expanding gases resulting from the firing of ammunition until after the former has moved a predetermined distance rearwardly, a gas contact area in said gas chamber to initiate movement of the actuator under the influence of the gas, the actuator initiating rearward movement of the bolt, the area of said gas contact surface being predetermined in accordance with the resistance of the moving parts of the gun, the force required to function said masses, and the working pressure generated by said low intensity cartridge so that when the said cartridge is fired, the explosion gases will react against said area to produce a force sufficient to overcome the resistance of the

moving parts and function said moving parts as satisfactorily as if high intensity ammunition were used.

2. In a machine gun having breech mechanism designed to resist and operate under the explosive force developed by a cartridge for said gun of normal calibre and explosive intensity; the combination of a barrel having a sub-calibre bore, bolt means including a bolt, a reciprocating actuator provided with means for chambering a sub-calibre cartridge of equal calibre with said sub-calibre barrel, said cartridge developing explosive gases of lower than normal intensity, said actuator being provided with a gas chamber member and having a gas chamber formed therein communicating with said cartridge chambering means, said gas chamber member being mounted in telescopic relationship with the rear portion of the barrel, a gas contact area in said gas chamber member adapted to initiate movement of the actuator under the influence of the explosion gases, said actuator initiating rearward movement of the bolt, the area of said gas contact surface being predetermined in accordance with the resistance of the moving parts of the gun, the force required to function said masses and the working pressure generated by said sub-calibre cartridge, so that when the said cartridge is fired, the explosion gases will react against said area to produce a force sufficient to overcome the resistance of the moving parts and function said moving parts as satisfactorily as if a cartridge of normal calibre and normal explosive intensity were used.

3. The combination with a firearm having bolt mechanism including a bolt, and a barrel, of means for effecting operation of said bolt mechanism upon the firing of the ammunition, said means including a movable actuator provided with a certain chamber, and means in addition to the usual barrel bore for venting a part of the expanding gases after the actuator has moved a predetermined distance rearwardly after the firing of the firearm.

4. In a gun of the kind described having a bolt, a barrel, an actuating member for the bolt mounted in telescopic relation to said barrel and arranged to form a gas chamber at the rear end of the barrel, as it moves rearwardly of the barrel, and means in addition to the usual barrel bore to effect opening of said chamber to the atmosphere after a predetermined rearward movement of the actuating member is effected to thereby exhaust the elements of combustion.

5. In a gun of the kind described having a bolt, a barrel, an actuating member for the bolt arranged to form a gas chamber as it moves rearwardly of the barrel, and means in addition to the usual barrel bore to effect opening of said chamber to the atmosphere after a predetermined rearward movement of the actuating member is effected to thereby exhaust the elements of combustion.

6. In a gun of the kind described having a bolt, a barrel, an actuating member for the bolt mounted in telescopic relation to said barrel and arranged to form a gas chamber at the rear end of the barrel as it moves rearwardly of the barrel, means to effect opening of said chamber to the atmosphere after a predetermined rearward movement of the actuating member is effected, and a cylinder having one end open and receiving the exhaust gases from said chamber to provide a space for depositing the elements of combustion.

7. In a gun of the kind described having a

- 5 bolt, a barrel, an actuating member for the bolt arranged to form a gas chamber as it moves rearwardly of the barrel, means to effect opening of said chamber to the atmosphere after a predetermined rearward movement of the actuating member is effected, and a cylinder having one end open and receiving the exhaust gases from said chamber to provide a space for depositing the elements of combustion.

10 8. In a gun of the kind described, a barrel, and a bolt mechanism actuating member having a rear end provided with a powder case chamber having a length shorter than the length of the powder case of the cartridge to be used therein, 15 a cartridge with the forward end of its powder case projecting forwardly of said powder case chamber, and means associated with the barrel and actuating member arranged to cause equalization of gas pressure within and without said 20 projecting end of the powder case.

25 9. In a firearm having a bolt mechanism including a bolt, means for actuating said bolt, ammunition chambering means cooperating with said bolt and bolt operating means, said ammunition chambering means including a powder case chamber having a length shorter than the length of the powder case of the cartridge to be used therein, a cartridge with the forward end of its powder case projecting forwardly of said powder 30 case chamber, and means associated with the barrel and the powder case chambering means arranged to cause equalization of gas pressure within and without said projecting end of the powder case.

35 10. In a gun of the kind described, the combination with a barrel having a free rear end portion and bored for small calibre ammunition, an actuating member including a rear portion bored to receive the powder case of such ammunition, 40 said actuating member also having a sleeve extending forwardly from said rear portion and fitting slidably over the rear end of said barrel, said sleeve and barrel being arranged to prevent the escape of expanding gases resulting from the 45 firing of ammunition until after the sleeve has moved a predetermined distance rearwardly and bolt mechanism actuated by the rearward motion of said actuating member.

50 11. In a gun of the kind described, the combination with a barrel having a free rear end portion and bored for small calibre ammunition, an actuating member including a rear portion bored to receive the powder case of such ammunition, said actuating member also having a 55 sleeve extending forwardly from said rear portion and fitting slidably over the rear end of said barrel, a gas-tight packing between the rear end of the barrel and said sleeve, and bolt mechanism actuated by the rearward motion of said 60 actuating member.

65 12. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having gas venting means closed when the sleeve is in ammunition firing position, and open after the sleeve has moved a predetermined 70 distance rearwardly, and bolt mechanism actuated by the rearward motion of said actuating member.

75 13. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having gas-venting means closed when the sleeve is in ammunition-firing position and open after the sleeve has moved a predetermined distance rearwardly, bolt mechanism actuated by the rearward motion of said actuating member.

14. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having gas-venting means closed when the sleeve is in ammunition firing position and open upon the sleeve moving a predetermined distance rearwardly, and bolt mechanism actuated by the rearward motion of said actuating member.

15. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having its inner face provided with a series of grooves extending from its open forward end to points spaced from its rear portion, the rearward movement of the sleeve being sufficient to uncover the rear ends of said grooves, and bolt mechanism actuated by the rearward motion of said actuating member.

16. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having its inner face provided with a series of grooves extending from its open forward end to points spaced from its rear portion, the rearward movement of the sleeve being sufficient to uncover the rear ends of said grooves, and bolt mechanism actuated by the rearward motion of said actuating member.

17. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having gas-venting means closed when the sleeve is in ammunition-firing position and open after the sleeve has moved a predetermined distance rearwardly, bolt mechanism actuated by the rearward motion of said actuating member.

18. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having gas-venting means closed when the sleeve is in ammunition-firing position and open after the sleeve has moved a predetermined distance rearwardly, bolt mechanism actuated by the rearward motion of said actuating member.

nism actuated by the rearward motion of said actuating member, and a cylinder surrounding the barrel and sleeve in spaced relation thereto and having the barrel secured in its forward end, said cylinder having its rear end open.

18. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having its inner face provided with a series of grooves extending from its open forward end to points spaced from its rear portion, the rearward movement of the sleeve being sufficient to uncover the rear ends of said grooves, bolt mechanism actuated by the rearward motion of said actuating member, and a cylinder surrounding the barrel and sleeve in spaced relation thereto and having the barrel secured in its forward end, said cylinder having its rear end open.

19. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having its inner face provided with a series of grooves extending from its open forward end to points spaced from its rear portion, the rearward movement of the sleeve being sufficient to uncover the rear ends of said grooves, bolt mechanism actuated by the rearward motion of said actuating member, and a cylinder surrounding the barrel and sleeve in spaced relation thereto and having the barrel secured in its forward end, said cylinder having its rear end open.

20. In a firearm, the combination of a barrel, a bolt mechanism actuating member, a powder case chamber cooperating with said actuator, said powder case chamber having a length shorter than the length of the powder case of the cartridge to be used therein, cocking means actuated by the rearward motion of said actuating member, a cartridge in said chamber having the forward end of its powder case projecting forwardly of said chamber and into the rear end of the barrel, the latter being recessed to receive the projecting end of the powder case, said recess having a chamfered peripheral wall to permit equalization of the gas pressure inside and outside of said projecting end.

21. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, bolt mechanism actuated by the rearward motion of said actuating member, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.

22. In a gun of the kind described, the combination with a barrel having a free rear end portion and bored for small calibre ammunition, an actuating member including a rear portion bored to receive the powder case of such ammunition, 5 said actuating member also having a sleeve extending forwardly from said rear portion and fitting slidably on the rear end of said barrel, a gas-tight packing between the rear end of the barrel and said sleeve, bolt mechanism actuated by the 10 rearward motion of said actuating member, the rear portion of the actuating member being proportioned to permit the forward end of a powder case to project therefrom, the rear end of the barrel being recessed to receive the projecting 15 forward end of the powder case, said recess having a chamfered peripheral wall to permit equalization of the gas pressure inside and outside of said projecting end.

23. In a gun of the kind described, the combination with a barrel having a free rear end portion and bored for small calibre ammunition, an actuating member including a rear portion bored to receive the powder case of such ammunition, 20 said actuating member also having a sleeve extending forwardly from said rear portion and fitting 25 slidably on the rear end of said barrel, said sleeve having gas-venting means closed when the sleeve is in ammunition firing position, and open after the sleeve has moved a predetermined distance rearwardly, bolt mechanism actuated by the rearward motion of said actuating member, the rear portion of the actuating member being proportioned to permit the forward end of a powder 30 case to project therefrom, the rear end of the 35 barrel being recessed to receive the projecting forward end of the powder case, said recess having a chamfered peripheral wall to permit equalization of the gas pressure inside and outside of said projecting end.

24. In a gun of the kind described, the combination with a barrel having a free rear end portion and bored for small calibre ammunition, an actuating member including a rear portion bored to receive the powder case of such ammunition, 45 said actuating member also having a sleeve extending forwardly from said rear portion and fitting 50 slidably on the rear end of said barrel, gas-tight packing between the rear end of the barrel and said sleeve, said sleeve having gas-venting means closed when the sleeve is in ammunition-firing position and open after the sleeve has moved a predetermined distance rearwardly, bolt mechanism actuated by the rearward motion of 55 said actuating member, the rear portion of the actuating member being proportioned to permit the forward end of a powder case to project therefrom, the rear end of the barrel being recessed to receive the projecting forward end of the powder case, said recess having a 60 chamfered peripheral wall to permit equalization of the gas pressure inside and outside of said projecting end.

25. In a gun of the kind described, the combination with a barrel having a free rear end portion and bored for small calibre ammunition, an actuating member including a rear portion bored to receive the powder case of such ammunition, 65 said actuating member also having a sleeve extending forwardly from said rear portion and fitting 70 slidably on the rear end of said barrel, said sleeve having its inner face provided with a series of grooves extending from its open forward end to points spaced from its rear portion, the rearward movement of the sleeve being sufficient to uncover the rear ends of said grooves, bolt 75

- mechanism actuated by the rearward motion of said actuating member, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
26. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having its inner face provided with a series of grooves extending from its open forward end to points spaced from its rear portion, the rearward movement of the sleeve being sufficient to uncover the rear ends of said grooves, bolt mechanism actuated by the rearward motion of said actuating member, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
27. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having gas-venting means closed when the sleeve is in ammunition-firing position, and open after the sleeve has moved a predetermined distance rearwardly, bolt mechanism actuated by the rearward motion of said actuating member, a cylinder surrounding the barrel and sleeve in spaced relation thereto and having the barrel secured in its forward end, said cylinder having its rear end open, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
28. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having gas-venting means closed when the sleeve is in ammunition firing position and open upon the sleeve moving a predetermined distance rearwardly, bolt mechanism actuated by the rearward motion of said actuating member, and a cylinder surrounding the barrel and sleeve in spaced relation thereto and having the barrel secured in its forward end, said cylinder having its rear end open, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
29. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, said sleeve having its inner face provided with a series of grooves extending from its open forward end to points spaced from its rear portion, the rearward movement of the sleeve being sufficient to uncover the rear ends of said grooves, bolt mechanism actuated by the rearward motion of said actuating member, and a cylinder surrounding the barrel and sleeve in spaced relation thereto and having the barrel secured in its forward end, said cylinder having its rear end open, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
30. In a gun of the kind described, the combination with a barrel having a free rear end portion and bored for small calibre ammunition, an actuating member including a rear portion bored to receive the powder case of such ammunition, said actuating member also having a sleeve extending forwardly from said rear portion and fitting slidably on the rear end of said barrel, gas-tight packing between the rear end of the barrel and said sleeve, said sleeve having its inner face provided with a series of grooves extending from its open forward end to points spaced from its rear portion, the rearward movement of the sleeve being sufficient to uncover the rear ends of said grooves, bolt mechanism actuated by the rearward motion of said actuating member, a cylinder surrounding the barrel and sleeve in spaced relation thereto and having the barrel secured in its forward end, said cylinder having its rear end open, the rear portion of the actuating member being proportioned to permit the forward end of a powder case to project therefrom, the rear end of the barrel being recessed to receive the projecting forward end of the powder case, said recess having a chamfered peripheral wall to permit equalization of the gas pressure inside and outside of said projecting end.
31. In a machine gun having breech mechanism and ammunition feeding means of such weight and resistance as to normally require high intensity ammunition to operate the same; the combination of a stationary barrel, bolt means including a bolt, a reciprocating actuator provided with means for chambering a low intensity cartridge, said actuator being provided with a gas chamber member and having a gas chamber formed therein, communicating with said cartridge chambering means, said gas chamber member being mounted in telescopic relationship with the rear portion of the barrel, a gas con-

tact area in said gas chamber member to initiate movement of the actuator under the influence of the gas, the actuator initiating rearward movement of the bolt, the area of said gas contact surface being predetermined in accordance with the resistance of the moving parts of the gun, the force required to function said masses, and the working pressure generated by said low intensity cartridge so that when the said cartridge is fired, the explosion gases will react against said area to produce a force sufficient to overcome the resistance of the moving parts and function said moving parts as satisfactorily as if high intensity ammunition were used, and means in addition to the usual barrel bore for venting a portion of the expanding gases from said gas chamber after the reciprocating actuator has moved a predetermined distance rearwardly after firing of the machine gun whereby any tendency of the actuator to freeze to the barrel is prevented.

32. In a machine gun having breech mechanism and ammunition feeding means of such weight and resistance as to normally require high intensity ammunition to operate the same; the combination of a stationary sub-calibre barrel, bolt means including a bolt, a reciprocating actuator provided with means for chambering a low intensity cartridge and having a gas chamber formed therein communicating with said cartridge chambering means, said gas chamber member being mounted in telescopic relationship with the rear portion of the barrel, a gas contact area in said gas chamber member to initiate movement of the actuator under the influence of the gas, the actuator initiating rearward movement of the bolt, the area of said gas contact surface being predetermined in accordance with the resistance of the moving parts of the gun, the force required to function said masses, and the working pressure generated by said low intensity cartridge so that when the said cartridge is fired, the explosion gases will react against said area to produce a force sufficient to overcome the resistance of the moving parts and function said moving parts as satisfactorily as if high intensity ammunition were used, and means in addition to the usual barrel bore for venting a portion of the expanding gases from said gas chamber after the reciprocating actuator has moved a predetermined distance rearwardly after firing of the machine gun whereby any tendency of the actuator to freeze to the barrel is prevented.

33. In a machine gun having breech mechanism and ammunition feeding means of such weight and resistance as to normally require high intensity ammunition to operate the same; the combination of a stationary barrel, bolt means including a bolt, a reciprocating chambered actuator provided with a powder case chamber having a length shorter than the length of the powder case of the cartridge to be used therein and carrying a low intensity cartridge with the forward end of its powder case projecting from the actuator ammunition chamber, said actuator having a gas chamber member and a gas chamber formed therein communicating with the ammu-

nition chamber of the reciprocating actuator, said gas chamber member being mounted in telescopic relationship with the rear portion of the barrel, a gas contact area in said gas chamber member to initiate movement of the actuator under the influence of the gas, the actuator initiating rearward movement of the bolt, the area of said gas contact surface being predetermined in accordance with the resistance of the moving parts of the gun, the force required to function said masses, and the working pressure generated by said low intensity cartridge so that when said cartridge is fired, the explosion gases will react against said area to produce a force sufficient to overcome the resistance of the moving parts and function said moving parts as satisfactorily as if high intensity ammunition were used, and means associated with the barrel and the powder case ammunition chamber arranged to cause equalization of gas pressure within and without said projecting end of the powder case whereby any tendency of the actuator to freeze to the barrel is prevented.

34. In a machine gun having breech mechanism and ammunition feeding means of such weight and resistance as to normally require high intensity ammunition to operate the same; the combination of a stationary barrel, bolt means including a bolt, a reciprocating chambered actuator provided with a powder case chamber having a length shorter than the length of the powder case of the cartridge to be used therein and carrying a low intensity cartridge with the forward end of its powder case projecting from the actuator ammunition chamber, said actuator being provided with a gas chamber member and having a gas chamber formed therein communicating with the ammunition chamber of the reciprocating actuator, said gas chamber member being mounted in telescopic relationship with the rear portion of the barrel, a gas contact area in said gas chamber member to initiate movement of the actuator under the influence of the gas, the actuator initiating rearward movement of the bolt, the area of said gas contact surface being predetermined in accordance with the resistance of the moving parts of the gun, the force required to function said masses, and the working pressure generated by said low intensity cartridge so that when said cartridge is fired, the explosion gases will react against said area to produce a force sufficient to overcome the resistance of the moving parts and function said moving parts as satisfactorily as if high intensity ammunition were used, means associated with the barrel and the powder case ammunition chamber arranged to cause equalization of gas pressure within and without said projecting end of the powder case, and means in addition to the usual barrel bore for venting a portion of the expanding gases after the reciprocating actuator has moved a predetermined distance rearwardly after firing of the machine gun whereby any tendency of the actuator to freeze to the barrel is prevented.

DAVID M. WILLIAMS.
